UNITED STATES PATENT OFFICE.

ALBERT D. GOODELL, OF MILLER'S FALLS, MASSACHUSETTS, ASSIGNOR TO
MILLER'S FALLS COMPANY, OF SAME PLACE.

IMPROVEMENT IN BIT-STOCKS.

Specification forming part of Letters Patent No. 139,667, dated June 10, 1873; application filed
April 30, 1873.

To all whom it may concern:

Be it known that I, ALBERT D. GOODELL, of Miller's Falls, in the county of Franklin and State of Massachusetts, have invented certain new and useful Improvements in Bit-Stocks, of which the following is a specification:

My invention relates to tool-holders or bit-stocks; and consists in a novel construction, combination, and arrangement of parts, which have for their object to allow of the instrument held in the tool-holder being rotated by imparting a reciprocating or semi-rotary motion to the holder, as will be fully set forth hereafter.

The several figures represent the upper portion of the grasping mechanism of a bit-stock or tool-holder.

Figure 1 shows the device in one position; Figs. 2 and 3, in two other positions. Fig. 4 is a vertical transverse section of Fig. 1 taken through its axis, and Fig. 5 represents a part in detail.

In boring holes or driving screws in situations where the tool-holder cannot be completely rotated considerable trouble has been experienced, and where the hole is being bored in such close proximity to a wall or other obstruction that the crank cannot be entirely revolved, the holder either has to be alternately detached from the tool and replaced again at each reciprocation, causing great inconvenience and loss of time, or the hole has to be bored obliquely into the wood.

To obviate this difficulty several devices have been employed, as ratchet-drills, universal-jointed tool-holders, &c., all of which were more or less unhandy, complicated, and expensive, and my invention is designed to obviate this, as follows:

A represents a part of the crank-handle of a tool-holder, the lower extremity of which is formed into a solid cylinder or hub, B. C is a portion of the socket of the holder, in which the grasping jaws (not shown in the drawings) work, and, instead of being, as usual, stationary in relation to the crank-handles, this socket is

capable of revolving on the hub B, it being held thereon by a pin, h, which passes tangentially through its sides and fits in the groove f cut in the periphery of the projection on the hub B. At equal distances apart, on the upper edge of the socket C, square slots or recesses e e are cut, and in the cylinder B, parallel with its axis, a chamber is drilled for the reception of the latch b. This latch is forced outward against the upper edge of the socket C by the spring c, and as the socket is revolved the latch enters the recesses or slots e in succession. d is a handle, which enters the latch-chamber by a hole through its top, and is secured to the head of the latch. By this handle d the latch may be adjusted so as to revolve the boring-tool in either direction, as is shown by the arrows in Figs. 1 and 3, or it (the latch) may be so arranged as to lock the socket C to the crank-handle, as shown in Fig. 2. This facility of manipulation renders it applicable to any tool-holder. For boring a hole or driving screws the latch will be arranged as in Fig. 1; for withdrawing the tool or extracting screws it would be arranged as in Fig. 3, and when in ordinary use as in Fig. 2. When the latch is in any of the recesses e, its square end b' prevents its rotating therein, and to change its position it is necessary to withdraw it and then alter its position.

I am aware that reversible tool-holders provided with a ratchet-and-pawl arrangement are not new, and I lay no claim to such, broadly; but

I claim—

The combination, with a tool-holder, of a series of ratchets or recesses, e e, and a pawl or latch, b, so constructed that the tool can be rotated in either direction and locked stationary to the handle by the same pawl or latch, substantially in the manner and for the purposes described.

ALBERT D. GOODELL.
